UNITED STATES PATENT OFFICE.

BARTHolemew P. BURNS, OF CHICAGO, ILLINOIS, ASSIGNOR OF ONE-FOURTH TO
ANDREW DOBSCHER, OF CHICAGO, ILLINOIS.

CHAISE LONGUE.

Application filed November 22, 1924. Serial No. 751,575.

This invention relates to improvements in chaise longues, and more particularly to improvements in the chaise longue forming the subject matter of my Patent Number 1,538,517, May 19, 1925.

The present invention has for one of its objects the provision of a chaise longue wherein the arm rests shall be carried solely by and have a fixed position with respect to the adjustable back rest, whereby to insure the supporting of the arms of the occupant of the chaise longue in a comfortable position in any adjustment of the back rest.

A further object of the invention is the provision of a chaise longue wherein the lower portions of the lateral and rear sides of the adjustable back rest shall telescopically embrace the adjacent and corresponding portions of the main frame, whereby to present a neat and finished appearance between the adjustable back rest and seat frame and completely conceal the means for counter-balancing the back rest and supporting it in adjusted position.

A further object of the invention is the provision of a chaise longue wherein the hinged connection between the adjustable back rest and the main frame shall be concealed by means which in itself shall present a neat and finished appearance.

A further object of the invention is the provision of a chaise longue wherein the front side of the adjustable back rest shall be of arcuate formation in longitudinal section, whereby to provide ample room in the main frame beneath the back rest for the means for counter-balancing the back rest and supporting it in adjusted position and to insure the greatest possible comfort to the occupant.

A further object of the invention is the provision of novel and simple means for counter-balancing the adjustable back rest and securing it in adjusted position.

A still further object of the invention is the provision of a chaise longue which shall be provided with a fixed as well as an adjustable back rest.

With the above and other objects in view, the invention consists of the construction, combination and arrangement of parts hereinafter fully described and claimed, and illustrated in the accompanying drawings, wherein:

Figure 1 is a perspective view of a chaise longue constructed in accordance with my invention, the adjustable back rest being shown in its highest adjusted position for use.

Figure 2 is a perspective view of the rear portion of the chaise longue with the adjustable back rest in its lowest adjusted position.

Figure 3 is a view in side elevation of the chaise longue with the upholstery removed and the seat shown in dotted lines.

Figure 4 is a sectional view taken on the plane indicated by the line 4—4 of Figure 2.

Figure 5 is a view in side elevation of the rear portion of the chaise longue with the upholstery removed, parts being in vertical section and other parts broken away to illustrate the hinged connection between the adjustable back rest and main frame.

Figure 6 is a detail sectional view taken on the plane indicated by the line 6—6 of Figure 4.

Figure 7 is a detail sectional view taken on the plane indicated by the line 7—7 of Figure 6.

Figure 8 is a detail sectional view of the latch drum and portions of the shaft and springs of the adjustable back rest counter-balancing and supporting means.

Figure 9 is a detail sectional view illustrating one of the carrying handles for the rear end of the chaise longue.

Figure 10 is a detail perspective view of the means for concealing the hinged connection between the adjustable back rest and main frame, and housing the forward ends of the lateral sides of the adjustable back rest.

Figure 11 is a detail sectional view taken on the plane indicated by the line 11—11 of Figure 1.

Figure 12 is a detail sectional view taken on the plane indicated by the line 12—12 of Figure 1.

Figure 13 is a detail perspective view of one side of the frame of the adjustable back rest.

Figure 14 is a detail sectional view taken on the plane indicated by the line 14—14 of Figure 13.

Figure 15 is a detail view illustrating a slightly modified form of the carrying handles for the rear end of the chaise longue,

Figure 16 is a detail sectional view taken on the plane indicated by the line 16—16 of Figure 5.

Figure 17 is a perspective view of the chaise longue provided with a fixed back rest.

Figure 18 is a detail sectional view taken on the vertical plane indicated by the line 18—18 of Figure 17.

Figure 19 is a detail perspective view of one end of the frame of the fixed back rest and portion of the main frame.

Figures 20 and 21 are detail perspective views illustrating the connection between the contiguous ends of the fixed back rest and the adjacent arm rest of the adjustable back rest, and

Figure 22 is a detail perspective view of a fragmentary portion of said adjacent arm rest.

Referring to the drawings by reference numerals, A designates the legs, B the main frame, C the seat, D the adjustable back rest, and E the arm rests of the chaise longue. The main frame B comprises sides 1 and 1^a, and ends 2 and 2^a. A cross brace 3 is secured to and between the sides 1 and 1^a adjacent the end 2. Cross rails 4 are secured to and between the sides 1 and 1^a to support the springs 5 upon which the seat C is mounted. The seat C occupies the major portion b and the back rest D the minor portion b' of the main frame B. The minor portion b' of the main frame B extends above the major portion b, and its upper edge extends downwardly and inwardly, as clearly shown in Figures 3, 4 and 5. The rear end 2 curves from its upper edge in a downward and inward direction for the greater portion of its height, and thence downwardly and outwardly, as clearly shown in Figure 4. All parts of the chaise longue are covered by upholstery.

To permit the occupant of the chaise longue to assume a most comfortable position, the back rest D is adjustably mounted upon the main frame B, and to permit the arms of the occupant to be comfortably supported in any adjusted position of the back rest D, the arm rests E are carried solely by and have a fixed position with respect to the back rest D. The back rest D is hinged as at 7 to the posts 8 secured to and rising above the upper edges of the sides 1 and 1^a at the juncture of the major and minor portions b and b' of the main frame B. The frame of the back rest D comprises side pieces 9 having upwardly extending portions 9^a and inwardly extending portions 9^b, and said side pieces are located outwardly beyond the sides 1 and 1^a of the main frame B. The upper edges of the portions 9^a and 9^b are of convex formation, and they are offset to provide shoulders 9^c. Stems 10 extend downwardly from the lower edges of the

portions 9^a and are located outwardly beyond the end 2 of the main frame B. Strips 11 similar to the portions 9^b are secured to the inner sides of said portions and spaced therefrom by blocks 12 and 13. Boards 14 of three-ply veneer are secured in rabbets 15 of the portions 9^b and to the stems 10. Their outer surfaces are flush with the outer surfaces of said portions 9^b, and their inner ends extend inwardly beyond the corresponding ends of said portions. One leaf of each of the hinges 7 is secured to each post 8, and the other leaves of the hinges are secured to the lower sides of the blocks 12. Above the hinges 7, the inner edges of the portions 9^b and strips 11, and the inner sides of the blocks 12 are recessed as at 15 to receive plates 16 which are secured in place by screws 17. The plates 16 are provided at their lower ends with downwardly curved extensions 16^a which overlie the hinges 7 and which have a snug fit in openings 18 in the rear edges of cap plates 19 for the upper ends of the posts 8. The posts 8 are provided with grooves 8^a for the reception of the extensions 16^a. Before the plates 16 and 19 are secured in place, they are covered with mohair or other suitable upholstering material. Corbel plates 20 which are secured to the outer sides of the posts 8, are also covered with mohair or other suitable upholstery material, and they are provided in their inner sides with recesses 21 to receive the projecting edges of the boards 14 and the upholstering material which is secured to these portions of the back rest D. The extensions 16^a, plates 19 and corbels 20, conceal the hinges 7 and establish a neat and finished appearance at the points where the back rest D is hinged. The arm rests E are secured to strips 22 which are in turn secured to the upper edges of the portions 9^b and strips 11 by dowel pins 23 and screws 24. The dowel pins 23 are secured to the portions 9^b and strips 11 and pass freely through openings in the strips 22 and arm rests E. The screws 24 extend inwardly from the lateral edges of the strips 22 and engage the dowel pins 23. The side pieces 9 are connected by a top cross bar 25 and by lower cross bars 26, the lower cross bars being secured to the stems 10. The strips 22 abut the shoulders 9^c and they are narrower than the arm rests E. A webbing 27 is secured to the cross bars 25 and 26. Cross rails 28 are secured to and between the portions 9^b and support the springs 29 for the inner side 30 of the back D. This side of the back is longitudinally curved to afford the greatest degree of comfort and to provide ample room in the main frame B for the reception of the means for counter-balancing and securing the back rest in adjusted position. The lower portion of the back rest D telescopes over the

minor portion b' of the main frame B and due thereto, and as the corbel plates 20 cover the inner edges of the lower side portions of the back rest, a neat and finished appearance is provided between the back rest and main frame B, and the means for counter-balancing the back rest and supporting it in adjusted position is concealed in any adjusted position of the back rest.

10 The means for counter-balancing the back rest and supporting it in adjusted position, comprises a shaft 31 which is secured at its ends to the lateral sides 1 and 1^a of the main frame B. The shaft 31 is held against rotation, and loosely mounted upon the central portion thereof is a drum 32 to which one end of a strap 33 is secured by means of a bolt 34. The other end of the strap 33 is secured as at 35 to the lower end of a yoke 36. The upper end of the yoke 36 is pivotally connected to one of the cross bars 28 by means of a bracket 37, and the yoke passes through braces 38 carried by another of the cross bars 28. A toothed wheel 39 is loosely mounted upon the shaft 31 at each side of the drum 32. Coiled springs 40 mounted upon the shaft 31 between the drum 32 and the wheels 39, are secured at their ends to the drum and wheels. A latch rod 41 is adapted to engage with a notched flange 42 fixed to the drum 32 to normally hold the drum against rotation, and said drum is adapted to support the back rest D against accidental downward movement through the medium of the strap 33 and the yoke 36. The latch rod 41 is slidably supported by a bracket 43 secured to a platform 44, and it is yieldingly held in engagement with the notched flange 42 by means of a spring 45. A shaft 46 which is provided at its end with operating knobs 47, is journaled in the sides 1 and 1^a, and provides means by which the latch rod 41 may be retracted when it is desired to either raise or lower the back rest D. The latch rod 41 is connected to the shaft 46 by an arm 48 secured to the shaft and a link 49 connected to the arm and latch rod. The springs 40 are adapted to be tensioned by rotating the toothed wheels 39 by a wrench 50, and the springs 40 are adapted to be held under tension by gravity actuated dogs 51. The dogs 51 cooperate with the toothed wheels 39 and are pivotally mounted as at 52 in brackets 53 secured to the platform 44. The tail pieces 54 of the dogs 51 contact with the upper side of the platform 44, and due thereto and to the engagement of the dogs 51 with the toothed wheels 39 the springs 40 are held under tension. A contractile spring 55 is secured at its upper end to the upper end of the yoke 36 and at its lower end to a pin 56 carried by the notched flange 42, and it tends to limit the upward adjustment of the back rest D. When it is desired to raise or lower the back rest D, the latch rod

41 is withdrawn from the notched flange 42 through the medium of the shaft 46. During the downward adjustment of the back rest D, the tension of the springs 40 is increased, and due thereto the back rest D will 70 when released be raised by the springs 40.

When it is desired to gain access to the hinges 7, the plates 16 and 19 and the corbel plates 20 are removed. The plate 16 may be readily removed after first removing the 75 arm rests E. Handles 57 are provided for the end of the chaise longue upon which the back rest D is positioned in order to permit the chaise longue to be readily moved from place to place. The handles 57 are slidably 80 mounted in brackets 58 secured to the sides 1 and 1^a, and are completely housed when not in use by the lower portion of the back rest D. To prevent the handles 57 from being entirely withdrawn from the brackets 58, 85 the former are each provided at one end with stop pins 59, the rear ends of the handles being provided with knobs 60. If desired the handles may be mounted for vertical movement as shown in Figure 15. In this 90 figure 57^a designates the handles which are slidably mounted in brackets 58^a. The handles 57^a are provided at their lower ends with stop pins 59^a and at their upper ends with horizontal grips 61 terminating in 95 knobs 62.

In Figure 17, the chaise longue is shown provided with a fixed back rest F. This back rest extends along the side 1 of the main frame B, and it may be of any suitable design and is upholstered throughout its entire length. The inner end of the frame of the back rest F comprises a post 8^a which is secured to and rises vertically from the side 1 and to which the top bar 63 of the frame is secured. The upper portion 8^b of the post 8^a is laterally enlarged in the direction of the adjacent arm rest E and transversely reduced for the reception by a recess 64 in the inner end of this arm rest, and thus prevents the formation of an opening between the inner end of the arm rest and the inner end of the back rest F, in any adjustment of the back rest D. The upper end of the post 8^a and the upper wall of the recess 63 are correspondingly curved, as shown at 8^c and 63^a, to permit the free adjustment of the back rest D. The post 8^a is provided with a cap plate 19^a and the arm rest E is provided with a plate 16^b respectively similar to the plates 19 and 16. The inner edge of the plate 16^b is curved to correspond to the curvature of the inner side of the back rest F. As the plates 16^b and 19^a are covered with upholstery, and as there is no possibility of the formation of an opening between the back rest F and the adjacent arm rest E, there is provided a neat and finished appearance between these parts.

From the foregoing description, taken in 130

connection with the accompanying drawings, the advantages of the construction of the chaise longue will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the invention as claimed.

What is claimed is:—

1. A chaise longue including a main frame, a back rest hinged to the main frame, a shaft carried by the main frame, a drum rotatably mounted upon the shaft, a yoke connected to the back rest, a strap connected to the drum and yoke, tensioned springs associated with the drum, means cooperating with the drum to retain the back rest in adjusted position, and a spring connected to the back rest and said drum and tending to limit the upward adjustment of the back rest.
2. A chaise longue comprising a main frame, posts secured to the main frame and provided with recesses in their lateral sides, a back rest hinged to the outer sides of the posts and having a hollow lower portion embracing an end portion of the main frame, said back rest having portions fitting in said recesses, and means for adjustably supporting the back rest.
3. A chaise longue comprising a main frame, posts secured to the main frame and provided in their upper ends with recesses, a back rest having sides, hinges connected to the inner edges of the sides between the upper and lower edges of the latter and to the posts, plate secured to the upper portions of the inner edges of the sides and having portions overlying the hinges and entering said recesses, and means for securing the back rest in adjusted position.
4. A chaise longue comprising a main frame, posts secured to the main frame and provided in their upper ends and outer lateral sides with recesses, a back rest having sides, hinges connected to the inner edges of the sides between the upper and lower edges of the latter and to the posts, plates secured to the upper portions of the inner edges of the sides and having portions overlying said hinges and entering said upper recess, said sides being provided below the plates with inwardly directed extensions

entering said side recesses, and means for adjustably supporting the back rest.

5. A chaise longue including a main frame, posts secured to the main frame, a back rest having lateral sides, hinges secured to the inner edges of the sides and to the adjacent sides of the posts, a plate secured to the inner edge of one of the sides above the hinge secured to said side and having a portion overlying the hinge, and a plate secured to the upper end of the post to which said side is hinged and having an opening for the reception of said portion of said first plate.

6. A chaise longue including a main frame, posts secured to the main frame, a back rest having lateral sides, hinges secured to the inner edges of said sides and to the adjacent sides of the posts, a plate secured to the inner edge of one of the sides above the hinge secured to said side and having a portion overlying the hinge, a plate secured to the upper end of the post to which said side is hinged and having an opening for the reception of said portion of said first plate, said post being provided at its outer side with a recess for the reception of the forward portion of said side, and a plate secured to said post over the recess therein.

7. A chaise longue including a main frame, a post secured to and extending above one side of the frame, a second post secured to and extending above the other side of the main frame and above said first post, and a back rest hinged to said first post and to said second post below the upper end of the latter, said back rest having a side provided with a recess for the reception of the upper portion of said second post.

8. A chaise longue comprising a main frame, a back rest hinged to the main frame and having side pieces consisting of upwardly extending portions and inwardly extending portions, stems extending downwardly from the lower edges of the upwardly extending back rest portions, boards secured to the inwardly extending back rest portions and to the stems, cross bars secured to the stems, said stems, boards and cross bars providing the back rest with a hollow rigid lower portion enclosing and telescopically associated with an end portion of the main frame, and means for securing the back rest in adjusted position.

In testimony whereof I affix my signature.

BARTHOLOMEW P. BURNS.
